FOLDED ARTICLE

Edwin Jacobson, Altadena, Calif.

Continuation of application Serial No. 117,830,
December 28, 1936. This application December
21, 1938, Serial No. 247,043

2 Claims. (Cl. 206—57)

The present invention relates to folded articles, such as napkins, towels and the like, and particularly to improvement in the method of folding such articles for storage within a dispensing cabinet. This application is a continuation of application, Ser. No. 117,830 heretofore filed by me on December 28, 1936.

It is one of the objects of the invention to provide an article of the class described folded in such a manner that, when a stack of such articles is placed within an open end dispensing cabinet, only one article can be manually withdrawn at a time.

Another object is the provision of a combination as above outlined, in which it is only possible to touch the one article which is in position for withdrawal, and in which the remaining articles within the cabinet are fully covered by this withdrawable article and for this reason protected from contamination by the hand reaching for the withdrawable article.

A drawing is hereto annexed, in which the combination of the invention is illustrated, and the structures illustrated in the drawing are herein-after fully described.

In the drawing:

Fig. 1 is a perspective view showing the manner in which the articles of the invention are shown folded for insertion into a dispensing cabinet.

Fig. 2 shows, in perspective, the framing of a dispensing cabinet in which the articles of the invention are stacked, and

Fig. 3 shows the article as it appears before folding and with dotted lines to indicate where the folds are to be placed.

The sheet 1, which may be a fabric or paper towel is first folded along the diagonal line 2 and thereupon folded in the same direction on the median line 3. When folded in this manner, the articles take the shape indicated in Fig. 1. A number of the folded towels are thereupon stacked together to form a pack of the proper thickness to fill a dispensing cabinet.

It is noticed that the diagonal folds 2, 2^a of the articles, as presented in Fig. 1, are directed alternately right and left, and this is preferable because it produces a better balanced pack in which each one of the unfolded portions 7 is better supported between two adjoining folded corners 8, and similarly the portions 7^a between two adjoining corners 8^a.

The dispensing cabinet may be of any desired construction, so long as it has an opening 5, somewhat smaller than the pack of towels stored therein. For this reason, no particular cabinet construction is shown in connection with the simple framing 4, of Fig. 2, the back of which is understood to be open for the insertion of the articles.

Upon examination of this view, it is noticed that the articles are held in position by the flange 6 of the front opening. It is furthermore noticed that only the diagonal fold 2^a is visible and that the unfolded portion 7^a appears behind this fold. Also that, in this manner, the open end of the framing 4 is entirely closed by the first article.

The articles of the invention are mainly intended for dispensing purposes within public lavatories, restrooms and the like, and the dispensing of paper towels for drying wet hands is primarily considered. Most people washing their hands in public places are not careful in their actions and motions, and the manner in which the wet hand or hands approach the towel to be withdrawn is not usually given thought. At times, when the face also has been washed, the user may grope blindly with the hands for the cabinet opening. But no matter how carelessly the user may act, or how clumsily his wet hands may contact the paper towel, it is seen that only the one exposed towel can be soiled in the course of withdrawal because the next following is completely covered.

It is also noticed that only one towel can be withdrawn at a time, because the folded edge 2^a alone is available for this purpose, and the only thing possible for the user to do, is to grip this edge and to pull thereon until the entire towel is withdrawn.

The opening 5 is now covered by the next following towel, and only the diagonal fold 2 is exposed as the only means of withdrawing this second towel.

While a preferred form of the invention is illustrated and described, I reserve the right to make minor changes and modifications within the scope of the appended claims.

I claim:

1. A stack of sheets, each sheet having a central fold to produce a sheet of double thickness, the sheets being stacked with the folded edge at the bottom, the front thickness of each sheet being bent inwardly between the two thicknesses on an angular line extending alternately from the right and left top corners of the front thicknesses downwardly, substantially to the respective opposite corners of said thickness.

2. In a combination with an open end rectangular container, a stack of sheets seated in said container for manual withdrawal therefrom, each sheet having a central fold to produce a sheet of double thickness, the sheets being stacked with the folded edge resting on the bottom of the container, the front thickness of each sheet being folded inwardly between the two thicknesses on an angular line extending alternately from the right and left top corner of the front thickness of each sheet downward, substantially to the respective opposite corners of said thickness.
